UNITED STATES PATENT OFFICE

WILLIAM IVOR BELL, OF CHELSEA, LONDON, ENGLAND

SYSTEM OF STORING MOTOR ROAD VEHICLES

Application filed June 29, 1929, Serial No. 374,905, and in Great Britain July 2, 1928.

This invention relates to storage systems and has particular reference to garages for motor road vehicles, the object of the invention being to enable a maximum number of 5 vehicles to be stored in a given floor space without detracting from the ability to readily put them in and take them out of store.

The improved system comprises essentially the use of a plurality of travelling platforms 10 each adapted to contain or hold any predetermined number of vehicles arranged either side by side or in any other suitable and convenient manner.

The length of these platforms is such that 15 their aggregate length is so much less than the space available for them as will provide for the formation of an alley way between any two platforms, longitudinal rows or any two rows of platforms and to one side of or 20 between any two of the platforms is a common alley way which preferably has an entrance at one end and an exit at the other end. Each platform is preferably of such a length that it will take two cars end on and of such 25 a width as will take the desired number of pairs of cars side by side. If this number is, say four, the platform will accommodate eight cars.

The platforms are adapted to run on rails 30 and may be provided with suitable mechanism whereby they can be propelled along their track.

The invention will now be more particularly described with reference to the accompanying drawings in which:—

Figure 1 is a diagrammatic layout for a garage for road vehicles situated between two streets.

Figure 2 is a plan view of one of the travelling platforms.

Figure 3 is an end view thereof.

Figure 4 is an end view on an enlarged scale of part of one of the travelling platforms showing a means for traversing same 45 and,

Figure 5 is an end view of the gearing.

The platforms 1 are each of such a length and width as will accommodate say two rows of four cars each, that is eight cars in all. 50 The platforms 1 are adapted to run on rail

tracks 2 arranged in parallel relation to each other and to a common alley way 3 preferably having an entrance at one end and an exit at the other as shown.

This common alley way 3 may be arranged 55 at any desired position between the moving platforms, according to the number of platforms arranged side by side, said alley way being preferably arranged mid way between the rows as shown in Figure 1.

The length of the platforms 1 is such that 60 their aggregate length is so much less than the space available for them as will provide for the formation of an alley way 4 arranged 65 at right angles to the parallel tracks between any two, or any two rows of platforms.

The rails 2 are laid so that their running 70 surfaces are approximately level with the ground surface and the platforms are each furnished with a plurality of girder elements 75 which serve not only to maintain the rigidity of the platform but as supports for the running wheels 6 and ramps 7.

Any suitable means may be provided for 75 traversing the platforms on their tracks; in the embodiment illustrated said platforms are furnished on the underside with racks 8 adapted to be engaged by toothed wheels 9 driven by suitably arranged gearing 10 driven by a motor 11.

In operation, if, for example, it is desired 80 to place a car in or remove one from say the compartment 12 of platform 13, it will first be necessary to traverse the platforms 13 to 21 in the direction of the arrow so as 85 to form an alley way at 22.

In the event of the storage garage being situated between two streets as shown in Figure 1, or if a street runs along only one end thereof the platforms 23—24 adjacent 90 said streets or street need not be arranged to move on rails as the cars in, or to be placed in the compartments of these platforms may be run directly out of or into same from the street.

If desired additional fixed storage compartments may, if space permits, be provided at 95 but if a street did not run parallel with said compartments and it was necessary to run cars down the alley way 4, certain of said 100

compartments 25 in line with the pillars 26 supporting the garage roof or floor above would, in certain cases, be useless.

What I claim is:

- 6 In a storage system, a building, a plurality of parallel tracks arranged on the available floor space of said building, a plurality of platforms each capable of receiving a plurality of vehicles arranged to travel on said
- 10 tracks in the direction of their length, means for traversing said platforms on said tracks, a common alley way arranged parallel with said tracks and with the length of the platforms, an alley way arranged at right angles to the parallel tracks capable of being formed between any two parallel rows of platforms and a plurality of fixed storage compartments arranged so as to be entered from the alley way arranged at right angles
- 15 to the parallel tracks and to the length of the platforms, the general arrangement being such that the whole available floor space, less the space required for the common alley way and the alley way arranged at right angles
- 20 to the parallel tracks, is employed for storage
- 25 purposes.

WILLIAM IVOR BELL.
